UNITED STATES PATENT OFFICE.

FRANK K. WARD, OF WASHINGTON, DISTRICT OF COLUMBIA.

DESIGN FOR A WAGON-BODY.

SPECIFICATION forming part of Design No. 21,420, dated March 22, 1892.

Application filed February 15, 1892. Serial No. 421,639. Term of patent 14 years.

To all whom it may concern:

Be it known that I, FRANK K. WARD, a citizen of the United States, residing at Washington, in the District of Columbia, have invented and produced a new and original Design for Delivery-Wagon Bodies, of which the following is a specification.

This design has for its object to provide a novel body for milk-delivery wagons, which is ornamental and presents a very attractive and handsome appearance.

The leading feature of the design resides in a wagon-body having a front neck, a rear step, and a longitudinally and transversely curved top extended at the front into a hood or bonnet which overhangs the neck and at its rear into a hood or bonnet which overhangs the neck and at its rear into a hood or bonnet which overhangs the rear step.

The design also consists in a wagon-body having a front neck, a rear step, a longitudinally and transversely curved top extended at the front into a hood or bonnet which overhangs the neck and at its rear into a hood or bonnet which overhangs the rear step, and vertically-arranged handle-bars at the rear, which curve toward each other at their lower end portions.

The design also consists in a wagon-body having a front neck, a rear step, a longitudinally and transversely curved top extended at the front into a hood or bonnet which overhangs the neck and at its rear into a hood or bonnet which overhangs the rear step, a wheel-arch, a panel above the wheel-arch, vertically-arranged handle-bars in front of the panel, and vertically-arranged handle-bars at the rear, having their lower end portions curved inward toward each other.

The design also consists in a wagon-body having a longitudinally and transversely curved top extended into front and rear hoods or bonnets and provided with side walls, which curve inward toward each other at their lower ends, and vertically-arranged rear handle-bars having their lower end portions curved inward toward each other.

The design is illustrated by the accompanying drawings, in which—

Figure 1 is a perspective view illustrating my design for the body of a milk-delivery wagon. Fig. 2 is a side elevation of the same, and Fig. 3 is a rear end elevation thereof.

In the accompanying drawing the numeral 1 indicates the sides of the body, which at their lower ends are curved inward toward 55 each other, as at 2.

The base of the body is provided with the wheel-arch 3, the front neck 4, and a dash 5, and the rear end wall of the body is provided with a doorway 6, bounded at the sides by 60 vertical ribs 7 and at the top by an arched rib 8.

The top of the body is curved longitudinally and transversely and at the front is extended into a hood or bonnet 9, which overhangs the 65 neck 4, and at the rear into a hood or bonnet 10, which overhangs a rear step 12.

The body is provided above the wheel-arch with a panel 13, and in front of this panel are arranged vertical handle-bars 14, offset from 70 the body and provided with ornamental tips 15 at their upper and lower extremities.

The rear end of the body is provided with vertically-arranged handle-bars 16, bent inward at their upper and lower extremities, as 75 at 17, and having their lower end portions curved laterally toward each other, as at 18, so that the lower portions of the handle-bars are brought nearer together than the upper portions thereof to harmonize with the curved 80 lower end portions 2 of the side walls 1 of the body.

The front of the body is provided with brackets 19, located under the front hood or bonnet 9, and the rear of the body is provided 85 with brackets 20, located under the hood or bonnet 10 and terminating at their lower portions in proximity to the upper extremities of the rear handle-bars 16.

The design provides a novel body for a 90 milk-delivery wagon, which is highly ornamental and presents a very attractive and handsome appearance.

What I claim is—

The design for a wagon-body, substantially 95 as shown and described.

In testimony whereof I have hereunto set my hand and affixed my seal in presence of two subscribing witnesses.

F. K. WARD. [L. S.]
